UNITED STATES PATENT OFFICE.

HARRY H. MYERS, OF HOBOKEN, NEW JERSEY, ASSIGNOR OF ONE-HALF TO
ROBERT C. MACKE.

MEMORANDUM-TABLET FOR TELEPHONES.

No. 856,177.

Specification of Letters Patent.

Patented June 4, 1907.

Application filed February 11, 1905, Serial No. 245,205.

To all whom it may concern:

Be it known that I, HARRY H. MYERS, a citizen of the United States, and a resident of Hoboken, in the county of Hudson, State 5 of New Jersey, have invented certain new and useful Improvements in Memorandum-Tablets for Telephones, of which the following is a specification.

My invention relates to improvement in 10 telephone memorandum attachments.

It provides an attachment for a telephone upon which a tablet or a roll of paper may be used for making memoranda, and also provides, where a roll of paper is used, means 15 for holding the roll of paper and means for cutting off the memoranda after it has been made.

In the accompanying drawings illustrative of my invention, Figure 1 shows a desk 20 telephone with my invention attached thereto. Fig. 2 shows a bottom plan view of my invention. Fig. 3 shows a side view of Fig. 2 taken through the center of the roll of paper and the center of the writing bed. Fig. 4 25 shows a side view of Fig. 2 from the right. Fig. 5 is a detail view. Fig. 6, is a detached view in perspective of a detail of the invention.

Similar letters of reference indicate similar 30 parts.

1 is a vertical standard of the ordinary desk telephone to which my invention is attached.

2 is an arm, one end of which, marked 2', 35 is made in the form of a semi circle so as to partially encircle the standard 1 of the telephone.

3 is a semi circular band made to correspond with the semi circular portion 2' of the 40 arm 2, having at one end a point 5, which projects through the hole 4 in the arm 2, and having at its other end a hole 6, which corresponds to a similar hole in the arm 2, so as to permit a screw 7 to pass through the holes, 45 holding the same together.

The end of the arm 2, opposite to the semi circular portion, is provided with two legs 8—8, so arranged that the screw 9 may pass between them and so that the screw head 10 50 may be screwed down tightly to hold the

writing bed 11, to which the screw 9 is fixedly secured in rigid position.

The writing bed 11 is made of metal or other suitable material and has attached to it at its upper portion a single piece of spring 55 wire 16', one end of which projects into the core of the roll of paper 15 upon which memoranda is to be made, and then is arranged so as to form a spring, as shown in Fig. 3, underneath the writing bed for giving a flexible 6c movement to the roll of paper and to act as a tension for holding the paper smoothly on the writing bed, and is then secured to the bed plate 11 at the point marked 12 in Fig. 3, and then passes up over the bed plate and 65 forms a tension spring 12', shown in Fig. 1, for holding the paper in position so that it will not crumple or wrinkle when being written upon, and also so that too much paper will not be unwound from the roll when the person using same pulls a portion of the paper 70 after having written upon it below the writing bed so as to detach it from the portion which is now exposed for writing. After passing over the bed plate, as shown in Fig. 75 1, the spring wire then again passes underneath the bed plate and forms a spring and projects into the other end of the roll of paper so as to properly support same in position. Attached to the lower end of the writing bed 11 is a plate 14 of any desired material, preferably metal, so arranged as to form a tension device for holding the lower end of the paper upon which a person is writing in proper position, and also to form a paper cutter 80 for cutting off that part of the paper upon which a memorandum has been written. In the drawings 15 represents the paper for making memoranda.

I also provide insulation 16 upon the inner 90 side of the semi circular portions 2' and 3, so as to prevent any current of electricity passing through the arm to the bed plate and other parts of the writing tablet.

Many modifications and changes may be 95 made without departing from the spirit of my invention.

Having thus described my invention, what I claim and desire to secure by Letters Patent is

In combination, a bed, and a holder secured thereto, said holder being formed of a single piece of wire bent into an approximate U-shape, the free end portions of the wire each being coiled on itself and terminating in offsets to engage a roll, the base of the U being bent in such a manner as to embrace an end of the bed.

In testimony whereof, I have signed my name to this specification, in the presence of two subscribing witnesses.

HARRY H. MYERS.
